Primary Examiner — Kevin Rudzinski*Assistant Examiner* — Sean D Lough(74) *Attorney, Agent, or Firm* — Rutan & Tucker LLP; Hani Z. Sayed(57) **CLAIM**

The ornamental design for the vent breather, as shown and described.

DESCRIPTION

FIG. 1 is a top, front, left side perspective view of the vent breather;

FIG. 2 is a bottom, rear, right side perspective view;

FIG. 3 is a front elevation view, the device being rotationally symmetric, and all elevation views being identical;

FIG. 4 is a top plan view;

FIG. 5 is a bottom plan view; and,

FIG. 6 is a top, front, left side exploded perspective view.
